UNITED STATES PATENT OFFICE.

CHARLES HARRIS, OF CHICAGO, ILLINOIS, AND MARTIN A. KATZ, OF CLEVELAND, OHIO.

DESIGN FOR A BOUDOIR BOX.

Application filed November 3, 1923. Serial No. 7,668. Term of patent 3½ years.

To all whom it may concern:

Be it known that we, CHARLES HARRIS and MARTIN A. KATZ, citizens of the United States, and residents, respectively, of Chicago, in the county of Cook and State of Illinois, and of Cleveland, in the county of Cuyahoga, State of Ohio, have jointly invented a new, original, and ornamental Design for Boudoir Boxes, of which the following is a specification, reference being had to the accompanying drawing, forming part thereof.

The figure is a perspective view of a boudoir box showing our new design.

We claim:

The ornamental design for a boudoir box as shown.

CHARLES HARRIS.
MARTIN A. KATZ.
